UNITED STATES PATENT OFFICE.

BENNY BERNSTEIN, OF NEW YORK, N. Y.

FASTENING FOR GLOVES, SHOES, &c.

SPECIFICATION forming part of Letters Patent No. 424,754, dated April 1, 1890.

Application filed July 23, 1889. Serial No. 318,438. (No model.)

To all whom it may concern:

Be it known that I, BENNY BERNSTEIN, a citizen of the United States, residing at New York city, in the county of New York and 5 State of New York, have invented a new and useful Improvement in Fastenings for Gloves, Shoes, Corsets, &c., of which the following is a specification.

My invention consists in a fastening for 10 gloves, shoes, corsets, &c., composed of a series of button-headed fastenings secured along one edge of the article, having two openings through each fastening for the passage of the lacing-cord, a series of eyelets, 15 preferably arranged in pairs along the opposite edge of said article, and a lacing-cord secured at one end to the lower edge of the article, being fastened and passed alternately back and forth through the apertures in the 20 fastenings and through the eyelets. It also consists in a fastening for gloves, &c., composed of a button-head having a divided shank formed into a loop between the head and shoe thereof for the lacing-cord, and washers 25 with perforations secured upon one edge of the article to be fastened, eyelets upon the opposite edge of said article, and a lacing-cord. It further consists in a lace-fastening for gloves, &c., composed of a button-head 30 having a diametric slot or depression formed in the head thereof, and having a divided shank and washers with perforations and adapted for use in connection with a cord, all constructed and adapted to operate substantially as and for the purposes as will be hereinafter more fully described, and pointed out in the appended claims.

Referring to the accompanying drawings, forming a part hereof, for a better understanding of the details of construction of my invention, Figure 1 is a plan view illustrating the two adjoining edges of an article—such as a glove, shoe, corset, &c.—to which my fastening is applied, said edges of the article 45 being shown as separated and not as in their fastened position. Fig. 2 is a detached view on an enlarged scale of the lace-fastening, and Fig. 3 is an edge view illustrating the position of the edges of the article when secured by my fastening. Fig. 4 is an enlarged view of the lace-fastening, the parts thereof being detached. Fig. 5 represents a view of

an umbrella provided with my lace-fastening for securing the free end of the cord or tape usually employed upon such umbrellas to retain the same in its closed position. Fig. 6 55 represent views in perspective of the reverse surfaces of the lace-fastening, illustrating the formation of the recess formed in said lace-fastening to receive and retain the lace or 60 cord. Fig. 7 is an edge view of the lace-fastening with its shank and washers. Fig. 8 represents transverse sections in different positions through the umbrella shown in Fig. 5, and Fig. 9 is a view illustrating a lady's 65 shoe supplied with my lace-fastening.

The letters *a b*, Figs. 1 and 3, indicate the adjoining edges of the article to be secured together. Upon the edge *b* double eyelets, as at *e e'*, are placed, while upon the other edge 70 the fastenings are secured, which fastenings are not placed opposite the eyelets but occupy an intermediate position upon the opposite edge of the article relative to said eyelets, for the purpose as will presently appear. 75

The fastening is, as shown in Fig. 4, composed of three pieces—a button-like head 1, having a divided shank 2, which shank forms part of said head and is formed into a loop 3 between the head and shoe, and two washers 80 4 and 5, each of which washers has three perforations, as at 6 7. When in position, as in Fig. 3, the washers 4 and 5 are placed upon each side of the article and the shank 2 of the head 1 passed through the central perforation 85 7 of each washer and the ends of said shank bent outward, as in Fig. 2, whereby the parts of the fastening will be securely held in place. No cutting or preparation of the article to receive the fastening is therefore necessary. 90 Within the top fastening, or each may be similarly constructed, is formed a diametric slot or depression, as at *d*, which depression is made tapering or wider at one end than at the other, for the purposes hereinafter explained. 95

C is the lace or fastening-cord, which is formed at intervals along its length with tapered enlargements *c*. A knot, as at *c'*, is made at one end of this cord, and it is then 100 passed up through the lower hole 6 of the washers 4 and 5, then through the loop 3 of the shank 2 between the head and shoe, and then down through the opposite hole in the

washers 4 and 5. Thence the cord passes through the lower set of eyelets *e*' on the opposite edge of the article and then back through the fastening, then through the next series of 5 eyelets *e* and back to the fastening until the top fastening is reached, when the cord is passed up through the lower holes, through the washers thereof, and then given a turn or two around the head or placed in the depression *d* in the face thereof, when the tapered enlargement *c* will prevent the cord slipping. To fasten the article, therefore, all that is necessary is to draw upon the cord until the edges of the article lap each other, when the 10 cord is slipped within the depression in the head of the top fastening, and is so held by the knot or enlargement of the cord fitting within the tapered recess of said head. To unfasten the article, the cord is lifted from 15 out of the depression in the head of the top fastening and the edges of the article drawn apart, when the cord will slip through the washers and eyelets. It will thus be seen that but one cord or lace is used in this fastening, 20 and when secured in place the edges of the article lap each other, so that the lace is concealed beneath and only the fastening appears, giving the appearance of a button-fastening. The two washers prevent injury to the article, 25 and the loop between the head and shoe is to receive the lace, whereby said head is held by said lace in addition to its shank. The alternate position of the fastening relative to the eyelets enables the edges of the 30 article to be brought close together one upon the other, so that the opening as well as the fastening lace or cord is concealed.

As shown in Fig. 5, the lace-fastening may be used to advantage for securing the cord 40 or tape of umbrellas, in which instance the fastening is secured to the fabric in the same manner as upon gloves, shoes, &c., and one end of the cord is secured to said fastening by having a knot in its end and then being 45 passed up through the holes in the washers thereof, as shown in Fig. 8. By simply passing the cord around the umbrella, then once or twice beneath the head of the fastening, and then down within the recess, the cord is 50 held secure in place, as in Figs. 5 and 8. The same result is accomplished when the fastening is used to secure a shoe, as in Fig. 9. In this instance only one cord or lace is used, and the cord may be free of knots. The usual 55 eyelets or lace-holders may also be used below the top fastening, as shown.

This form of lace-fastening may be employed for various purposes, and it is evident that the operation of lacing and unlacing 60 boots, gloves, &c., is much easier accomplished than when two cords are employed and a bow-knot has to be made, all that is

necessary being to draw upon the cord until the edges of the article being fastened are brought sufficiently tight together, then give 65 the cord a turn around the fastening, and then place it within the recess in the face of the same; and, as shown in Fig. 6, this recess or diametric depression formed in the head of the fastening is cylindrical in cross-section, and is of a tapered, tubular, or funnel shape from end to end. The slot or opening across the face of the fastening is quite narrow, and its edges may be parallel, as in Fig. 6, or slightly diverging, while the opening 70 below the face of the head is slightly larger than the slot. The object of this is that only a narrow opening across the face of the fastening is apparent, and the lace or cord will lie entirely below the face of the fastening, 75 the chamber for the cord being, as before stated, cylindrical and tapered from end to end, as shown in Fig. 6, so that the cord will fit close and snug therein, and wear or cutting thereof will be prevented. 80

Having thus fully described my invention, what I claim as new, and desire to secure by Letters Patent, is—

1. A fastening for gloves, &c., consisting of a series of button-headed fastenings secured 90 along one edge of the article having two openings through each fastening for the passage of the lacing-cord, a series of eyelets arranged in pairs along the opposite edge of said article, and a lacing-cord secured at one 95 end to the lower edge of the article, being fastened and passed alternately back and forth through the apertures in the fastenings and through the eyelets, for the purposes specified. 100

2. A fastening for gloves, &c., consisting of the button-head having a divided shank formed into a loop between the head and shoe thereof for the lacing-cord, and washers with perforations secured upon one edge of the article to be fastened, eyelets upon the opposite edge of said article and lacing-cord, all constructed and arranged substantially as and for the purposes specified. 105

3. A lace-fastening for gloves, &c., consisting of the button-head having a diametric slot or depression formed in the head thereof, and having a divided shank and washers with perforations, substantially as described, and adapted for use in connection with a 110 cord, for the purposes specified. 115

In testimony that I claim the foregoing as my own I have hereto affixed my signature in presence of two witnesses.

BENNY BERNSTEIN.
